CLAIM

The ornamental design for a cooler tote, as shown and described.

DESCRIPTION

FIG. 1 is a front perspective view of the cooler tote claimed herein;

FIG. 2 is a front elevation view thereof;

FIG. 3 is a rear elevation view thereof;

FIG. 4 is a side elevation view thereof;

FIG. 5 is a side elevation view thereof;

FIG. 6 is a top plan view thereof; and,

FIG. 7 is a bottom plan view thereof.

The shorter spaced broken lines in the figure views depict stitching, which does form a part of the claimed design.

The longer spaced broken lines illustrate portions of the cooler tote and form no part of the claimed design.

1 Claim, 6 Drawing Sheets
